UNITED STATES PATENT OFFICE.

MAY C. CHRISTY, OF CLEVELAND, OHIO; JAMES CHRISTY ADMINISTRATOR OF SAID
MAY C. CHRISTY, DECEASED.

LAUNDRY APPLIANCE.

Application filed August 28, 1923. Serial No. 659,719.

To all whom it may concern:

Be it known that I, MAY C. CHRISTY, a citizen of the United States, residing at Cleveland, in the county of Cuyahoga and State of Ohio, have invented certain new and useful Improvements in a Laundry Appliance, of which the following is a specification.

My invention relates to laundry appliances, and my general object is to provide an improved hand rubbing device which may be used in connection with a corrugated wash board to expedite the work of hand washing and to promote thorough and complete cleansing of clothing or other fabrics. A further object is to provide a hand rubbing appliance faced with rubber, preferably corrugated on angular intersecting lines to provide numerous small projections adapted to effect a medium friction upon one side of the goods while the other side is in rubbing engagement with the relatively larger and coarser corrugated surface of a wash board. Another object is to connect a supplemental rubbing appliance to a wash board in a simple and practical way whereby the two devices may be conveniently handled and manipulated and used together or separably as occasion may require.

In the accompanying drawing, Fig. 1 is a perspective view of a wash board and my improved rubbing appliance connected together and shown in working position within a wash tub. Fig. 2 is a perspective view of my improved rubbing appliance alone.

Fig. 3 is a perspective view of a wash board and my improved rubbing appliance operatively connected to the upper end of the wash board.

The invention comprises a flat rectangular rubbing member or block 2 which may be made of wood or other material. An elongated handle 3 having incurved or slanting sides 4 extends lengthwise over the middle of the block to provide a comfortable hand grip for both hands and to permit a uniform pressure to be applied to opposite ends of the block. A thin sheet 5 of rubber or rubber coated fabric is nailed or otherwise affixed to the flat bottom of block 2, and the main body of this sheet is preferably formed with a moderately roughened rubbing surface 6 to promote washing of the goods and to produce sufficient friction to move the goods over the corrugated body 7 of a wash

board 8 when the block is manipulated with that end in view. The rubbing surface 6 is preferably composed of a multiplicity of small rubber studs or projections closely set or related, and these projections may be of the form shown or any other suitable shape. The rubbing surface being formed of rubber a yielding or resilient rubbing effect is produced and by applying pressure variously the friction on the goods may be lessened or increased correspondingly and the rubbing block either moved over the goods itself or the goods carried over the corrugated wash board with the rubbing block.

In Fig. 1, I show rubbing member 2 connected to the legs 9 of wash board 8 by an articulated wire frame, comprising a bail 10 pivotally united with handle 3, and a pair of wire links 11 hinged to the extremities of the side arms of the bail and to the inner sides of legs 9 of the wash board. The joints may be sufficiently loose or free to permit rubbing member 2 to be moved freely within limits in a lateral direction upon the corrugated body 7 of the wash board, and member 2 may be reciprocated the full length of the corrugated body without hindrance and also raised and removed apart therefrom. The articulated connections also permit rubbing member 2 to be thrown forward and folded over the front wall of the wash tub, that is to say, placed temporarily out of the tub while the wash board is being used separately for any reason. Rubbing member 2 may also be turned upon the connecting portion 12 of bail 10 to place rubbing surface 6 uppermost so that exceptionally fine fabrics may be scrubbed or washed solely upon this finely corrugated or moderately roughened rubber surface.

In Fig. 3 I show rubbing member 2 connected by an articulated wire frame to the upper end of a wash board instead of to the lower end as in Fig. 1. In this form of the invention the side arms of a bail 14 are pivotally connected to a second wire bail 15 having a cross connection 16 fastened in hinged union with the wash board frame by means of staples 17 driven into the side bars relatively near top cross piece 18. A jointed connection of this kind permits member 2 to be operated freely back and forth over the corrugated body of the wash board and bail 15 may be wide enough to permit its arms to clear the side bars of the wash board and

to permit member 2 to be turned over the top and to the rear.

In Fig. 3 the wash board is lying flat or horizontally, and it may be used in this way with rubbing member 2, but it may also be placed upright or in an inclined position and used in the same way as delineated in Fig. 1.

In use this invention lessens the labor of rubbing and washing as compared with the use of a wash board alone, and the work of washing is greatly expedited and also more efficiently accomplished.

Briefly, goods which are otherwise difficult to wash absolutely clean can be perfectly

cleansed with quickness and despatch with this device, and both fine and coarse fabrics can be thoroughly washed without damage.

What I regard as my invention or discovery, and desire to claim, is:—

A laundry hand appliance adapted to be used co-operatively with the corrugated surface of a washboard, consisting of a solid flat rubbing block and a thin finely-corrugated rubber-coated sheet of textile fabric affixed to the bottom face thereof.

In testimony whereof I affix my signature here this 25th day of August, 1923.

MAY C. CHRISTY.
